RAZOR HANDLE

Paul A. Braginetz, Stanton, Va., assignor to
Philip Morris Incorporated, New York, N.Y.

Filed May 22, 1975, Ser. No. 579,900

Term of patent 14 years

Int. Cl. D28—03

U.S. CL. D95—3 A

FIG. 1 is a perspective view of a razor handle showing any new design, color being depicted schematically;

FIG. 2 is an edge elevational view thereof;

FIG. 3 is a side elevational view thereof, both sides being the same; and

FIG. 4 is a fragmentary view on enlarged scale of the segment depicted by the circle A in FIG. 3 and showing with greater clarity the coloration of the razor handle.

I claim:

The ornamental design for a razor handle, as shown and described.
